S. S. SMITH

RAILROAD TIE

Filed July 7, 1922

Inventor:
Sidney S. Smith
by S. W. Bates Atty.

UNITED STATES PATENT OFFICE.

SIDNEY S. SMITH, OF CORINNA, MAINE.

RAILROAD TIE.

Application filed July 7, 1922. Serial No. 573,395.

To all whom it may concern:

Be it known that I, SIDNEY S. SMITH, a citizen of the United States, residing at Corinna, in the county of Penobscot and State of Maine, have invented certain new and useful Improvements in Railroad Ties, of which the following is a specification.

My invention relates to concrete railway ties and means for connecting the rail with the tie.

In the use of concrete ties, the most difficult problem is to join the tie and the rail in such a way that the rail is held firmly and so secured that although easily disconnected it cannot accidentally become loosened or freed.

My invention particularly relates to a connection by which the rail is held on the tie with a locking device easily applied, easily locked and easily removed when its removal is desirable.

In the form in which I prefer to construct my invention, I make use of a tie of suitable concrete having a substantially vertical opening therethrough with one of its walls substantially coincident with the operative edge of the rail flange.

The rail is held down by the head of a retaining spike which overlaps the flange, the lower portion of the spike having a projection which engages a cut-under portion of the wall of the opening.

The retaining spike with its projection is forced against the wall by a keeper which fills the balance of the recess not occupied by the spike and the spike and keeper are removably locked together by a split pin or other similar device.

I show in the accompanying drawing the preferable form of my invention but I desire it to be understood that other forms may be used while keeping within the terms of the appended claims.

Referring to the drawing:

Fig. 1 is a section taken cross-wise of the rail and lengthwise of the tie, taken on the line 1—1 of Fig. 2.

Fig. 2 is a section on the line 2—2 of Fig. 1 and,

Fig. 3 is a section taken on the line 3—3 of Fig. 1.

In the drawing, 3 represents the rail, 10 is its flange and 4 is the concrete tie upon

which the rail rests. The rail is held on the tie by means of a retaining spike of which 5 is the head and 6 the shank.

The face of the spike fits up against the vertical face 8 which forms one side of a substantially vertical opening or slot extending entirely through the tie, the face 8 being substantially coincident with the edge of the flange 10 of the rail; that is, so that the head of the spike will extend over the flange of the rail.

At some part of the vertical wall 8 is a cut-under portion 9 preferably formed with an inclined surface connected with the vertical part of the wall 8. A projection 7 is formed on the lower end of the spike extending into the cut-under portion 9 and engages therewith.

Means are provided for holding the spike in the position described so that it cannot be withdrawn by a lifting force applied to the spike.

For this purpose, I form a keeper or key 11 adapted to fit against the back face of the spike 6 and filling the space between the spike and the back or side of the recess opposite the wall 8, namely, the wall 12. At the upper end of the keeper 11 a short distance above the upper surface of the tie is a head or offset 13 under which a lifting bar may be inserted to lift the keeper and release the spike. For the purpose of forcing the keeper against the back edge of the spike and holding the same solidly in contact with the wall 8, I form immediately below the head an inclined surface 14 and at the lower end of the keeper a similar surface 15.

Both these surfaces are preferably formed parallel and when the keeper is forced downward they both act to force the spike solidly into contact with the wall 8.

In order to insure the contact of both the upper and lower ends of the spike and the wall I cut away a central portion 16 of the keeper so that if the central portion of the spike is not in line with the top and bottom the pressure of the keeper will be concentrated on those points.

For the purpose of limiting the motion of the keeper downward in relation to the spike, I form on the back side of the spike at its lower end a ledge or shoulder 17 which engages with the lower end of the keeper.

On the back side of the lower end of the spike is a projection 18 formed opposite the projection 7, the upper end of said projection terminating in the shoulder 17.

5 Inclined edges of the projections 7 and 18 are preferably parallel so that as the spike is lifted, the lower end will slide out from the inclined portion of the slot which is formed with parallel, opposing surfaces.

10 From the lower end of the spike, the opening in the tie is continued through the bottom of the tie so that the entire opening can be cleared out before the spike and its keeper are inserted and whenever it is necessary to do so.

15 The spike and the keeper are locked together to hold them in position by a double pin 20 extending through a suitable opening, half of which is in the spike and half in the keeper.

20 By the removal of the pin 20 the keeper may be lifted by a bar under the projection 13 and having thus loosened the spike the latter may be readily pulled out from the recess in the tie.

25 It will be seen that my means of securing the rail and the tie together are extremely simple. The rail is held downward by the strength of the spike securely locked in the body of the concrete and whatever jar may come by the use of the track the spike is held solidly in place, although easily removed when desired.

30 The vertical opening through the tie is, of course, carefully formed so as to exactly contain the spike and its keeper and when they are in place a solid body is formed, firmly secured to the rail so that it cannot be disturbed by any jar or motion which

may take place by the movement of the rail when in use.

40 The device is designed to be used on both sides of the rail.

I claim:

1. A rail support including a concrete tie having a vertical recess extending therethrough, one of the walls of said recess being substantially coincident with the edge of the rail flange, said wall having a cut-under portion, a retaining spike having its head overlapping said flange and having a lateral projection engaging said cut-under portion and having a ledge or shoulder formed at its lower end, a keeper for said spike between the same and the rear wall of said recess, said keeper having inclined surfaces for forcing it into contact with said spike, the lower end of said keeper contacting with said shoulder.

2. A rail support including a concrete tie having a vertical recess extending therethrough, one of the walls of said recess being substantially coincident with the edge of the rail flange, said wall having a cut-under portion, a retaining spike having its head overlapping said flange and having a lateral projection fitting into said cut-under portion and a keeper for holding said spike in position and having a projection extending over the upper surface of the tie for providing a bearing for removing said keeper, a portion of the material being cut away between the spike and keeper at their central portion to limit their contact to the ends.
